UNITED STATES PATENT OFFICE.

BERNARD MORGENTHAU, OF NEW YORK, N. Y.

LOCK.

1,410,828.

Specification of Letters Patent. Patented Mar. 28, 1922.

Application filed December 16, 1919. Serial No. 345,372.

To all whom it may concern:

Be it known that I, BERNARD MORGENTHAU, a citizen of the United States, and a resident of New York, in the county of New York and State of New York, have invented certain new and useful Improvements in Locks, of which the following is a specification.

The present invention relates to improvements in locks, and has for its main object to provide a lock with a locking bolt, having, besides the usual sliding motion, a rotary movement, whereby it becomes practically impossible to pick the lock either by skeleton or false keys or by sharp-pointed instruments.

Another object of the invention is to provide a lock of the character mentioned which is adapted for manufacture on a commercial scale, or in other words one which is not so difficult to make as to be beyond the reasonable cost of such a device.

With these and other objects in view, which will more fully appear as the nature of the invention is better understood, the same consists in the combination, arrangement and construction of parts hereinafter described, pointed out in the appended claims and illustrated in the accompanying drawings, it being understood that many changes may be made in the size and proportion of the several parts and details of construction within the scope of the appended claims without departing from the spirit or sacrificing any of the advantages of the invention.

One of the many possible embodiments of the invention is illustrated in the accompanying drawings, in which:—

Figure 1 is a front elevation of a lock constructed in accordance with the present invention, its face plate being removed in order to show its interior construction and its locking bolt being shown in its retracted position; Fig. 2 is a similar elevation with the bolt in its projected position; Fig. 3 is a section taken on line 3—3 of Fig. 2; Fig. 4 is a section taken on line 4—4 of Fig. 2; Fig. 5 is a section taken on line 5—5 of Fig. 1; and Fig. 6 is an inner view of the face plate of the lock, on a smaller scale.

In the drawings, the numeral 10 indicates a lock casing, mounted in any suitable manner upon the inner face of a door 11, said lock casing being in alignment with a keeper 12 on the jamb 13. Within the casing is

slidably and oscillatably disposed a locking bolt 14, having a transverse head 15 upon its front end and a flat enlargement 16 upon its rear end. The bolt extends through a bearing plate 17 that is preferably made integral with the lock casing, the said bolt being guided in its sliding movement by lugs 18, one of these lugs bearing against a ledge 19 upon the back plate 20 and the other lug 65 against a ledge 21 on the face plate 22 of the said casing. These two ledges are disposed in front of the bearing plate 17 and extend toward but stop short of the end plate 23 of the casing. The purpose of this arrangement will be described hereinafter. The lugs extend transversely of and are fixed to the bolt 14.

The transverse head 15 of the bolt is adapted to be projected through a vertical slot 24 in the end plate 23 and through a slot 25 in the keeper 12. These two slots have obviously a greater length than width, are in alignment with each other, when the door is closed, and lead to a recess 26 in the keeper, permitting the bolt to be given approximately a quarter of a turn, when the transverse head thereof is disposed within said recess.

On the flat enlargement 16 are formed two spaced shoulders, denoted by the numerals 27 and 28, against which is adapted to bear a cam 29, the latter being fixed to a spindle 30, which is rotatably mounted in a bearing 31 on the face plate 22 of the casing. With the spindle is connected a projection 32 upon a key plug 33, that is mounted and adapted to turn in a cylinder 34. This plug and cylinder form part of a so-called "cylinder" lock, a detailed description of which is not necessary as it is well-known and does not form part of the present invention. The key is insertable into the key plug from the outside. Below the shoulder 27 is formed on the enlargement 16 a cam face 35, with which co-acts the cam 29 above referred to, the arrangement being such that the cam 29 causes the bolt 14 to turn and the flat projection to tilt forward into the position shown in Fig. 3 of the drawings, 100 when the cam 29 turns in the direction of the arrow shown in Fig. 2 of the drawings and acts upon the said cam face. The turning movement of the locking bolt is limited by a stop 36 on the face plate 22, (Fig. 3). 110 The movement of the cam 29 is limited by a spring 37 in the lock casing, as clearly

shown in Fig. 2 of the drawings. When the parts are in these positions, the key is insertable from the outside into the key plug. In order to prevent the bolt from rotating 5 backwards, that is to say from the positions shown in Figs. 2 and 3 of the drawings into the position shown in Fig. 1 of the drawings, there is provided a spring 38, bearing against one of the lugs 18.

10 The operation of this device is as follows: In the positions shown in Figs. 2 and 3 of the drawings, the locking bolt is shown in its projected position, in which its transverse head 15 is disposed within the recess 15 26 in the keeper and projects partly across the slot 25 in the said keeper (Fig. 4). In these positions, the cam 29 is held in dotted position shown in Fig. 2 of the drawings by the spring 37. The door is unlocked from 20 the outside by inserting a key into the plug 33 and turning the latter in the required direction so as to rotate the cam clockwise. After this cam has ridden over the cam face 35 on the enlargement 16, it contacts with 25 the flat face of the said enlargement and first causes the bolt to be turned, so as to bring its head in alignment with the slots 25 and 24 in the keeper and lock casing, respectively. A further rotation of the said cam 30 brings the latter into contact with the shoulder 28 on the enlargement 16, retracting the said bolt until the elements are brought into the positions shown in Fig. 1 of the drawings, in which the transverse head 15 of the 35 bolt is withdrawn from the keeper and seated in the slot 24 in the end plate 23 of the lock casing. The door is thus adapted to be opened. It is to be observed that, when the locking bolt is retracted from the keeper, the 40 flat projection 26 is disposed parallel to the back plate 20 of the lock casing, the lugs 18, in co-operation with the ledges 19 and 21, preventing a rotation of the locking bolt, when withdrawn from the keeper.

45 In order to lock the door with the ele-

ments shown in Fig. 1 of the drawings, the cam 29 is rotated in the direction of the arrow shown in Fig. 1 of the drawings adjacent the same, whereby first it acts on the shoulder 27, causing the bolt to slide forward and its head 15 to be seated in the recess in the keeper. A continued rotation of the cam 29 in the same direction brings the said cam onto the cam face 35, whereby the bolt is given approximately a quarter turn, so that its head 15 is disposed across the slot 25 in the keeper (Fig. 4). It is to be observed that a rotating motion of the bolt can take place only after the lugs 18, in the forward movement of the bolt, have passed the ledges 19 and 21. The spring 38, bearing against one of the lugs 18 (Fig. 2), keeps the bolt in its locking position, as it prevents a turning of the bolt. The cam is then further rotated until it is stopped by its spring 37, when the key may be withdrawn.

What I claim is:—

In a door fastening, the combination with a lock casing having a slot in one of its end faces, of a recessed keeper provided with a slot in alignment with the slot in said lock casing, a locking bolt slidably and oscillatably disposed within said lock casing, a head on said locking bolt seated in the slot in said casing, an enlargement upon the inner end 75 of said bolt made integral therewith, said enlargement being provided with two spaced shoulders and a cam face, and a cam rotatably mounted upon said lock casing co-acting with said cam face and shoulders, 80 said cam in its rotation shifting longitudinally said bolt when acting on said shoulders and giving said bolt a partial turn when acting on said cam face, to give the bolt a partial turn when said head is disposed 85 within the recess in said keeper.

Signed at New York, in the county of New York and State of New York, this 15th day of November, 1919.

BERNARD MORGENTHAU.
